UNITED STATES PATENT OFFICE.

REGINALD FOWLER REED, OF TORONTO, ONTARIO, CANADA.

WATER-COIL.

1,081,332.

Specification of Letters Patent. Patented Dec. 16, 1913.

Application filed August 12, 1912. Serial No. 714,747.

To all whom it may concern:

Be it known that I, REGINALD FOWLER REED, of the city of Toronto, county of York, Province of Ontario, Canada, a subject of the King of Great Britain, have invented certain new and useful Improvements in Water-Coils, of which the following is a specification.

My invention relates to improvements in water coils, and the principal object of my invention is to construct water coils in which water is to be heated or steam generated, so that the condensation collecting thereon will be drained off without any danger of the same extinguishing any portion of the flame of the burner underneath the same, the burner-rings of which must be placed in a particular position. And another object of my invention, in its preferred form, is to provide means for binding the convolutions of the water coil in position, and so construct the same that the condensation collecting thereon will be caused to accumulate at certain points so 25 that it may be disposed of without coming in contact with the burner.

Another object of my invention is to inclose the water coil, as well as the burner thereunder, in a casing, the removable cover 30 or top of which is constructed so as to provide plenty of room above the water coil so as to insure proper air circulation to facilitate the combustion of the gas.

Further objects of my invention will be 35 set forth in the following specification.

Generically considered, my water coil is composed of a plurality of convolutions, the contiguous ones being spaced a short distance apart and placed so that any given 40 convolution extends a sufficient distance underneath the one immediately thereabove in order that the condensation may drain from one convolution to another, and collect on the lowermost convolution. Supporting or 45 retaining members are provided in my preferred form of construction, for the convolutions of the water coil, and the members extending below the said convolutions are so shaped as to cause any condensation accumulating thereon to drop from given positions, as hereinafter more particularly set forth.

Figure 1 is a vertical central transverse section through a water coil constructed according to my preferred form of invention, and through a suitable casing therefor.

This view shows in side elevation suitable supporting means for the convolutions, and a suitable gas burner, parts of which are shown in section. Fig. 2 is a plan view of a suitable burner, certain parts being broken away to illustrate construction. Fig. 3 is a plan view of the major portion of the upper supporting plates for my preferred form of water coil, and Fig. 4 is a side elevation of a section of one of the supporting bars for the under side of the sections of my said water coil.

In the drawings like characters of reference indicate corresponding parts in each figure.

It is well known by those skilled in this art, that in the ordinary water coil, the condensation will drop down upon a number of the holes of the gas burner, and so extinguish part of the flame, thus impairing the efficiency of the water heater or steam generator. Not only is this disadvantage present, but as a further result of neglect to properly drain off the condensation, the supporting parts for the water coil, as well as the casing inclosing these parts, become 75 badly rusted and consequently do not last as long as they should.

In the water coils I have constructed for use, the convolutions are spaced about a sixteenth of an inch apart, and the external diameter of the tubing used is substantially a quarter of an inch. Of course the space separating the said convolutions will depend upon the external diameter of the piping or tubing, as will be understood by one skilled in this art.

In my preferred form of construction, the convolutions progressively increase in diameter from the top to the bottom of the coil, in one side of the sections, and decrease in diameter from the top to the bottom of the coil in the other side of the said sections, as will be more particularly set forth in the following specification. The gas orifices in the burner used with all forms of my water coil must essentially be positioned within the periphery of the water-coil and out of alignment with the lowermost convolutions so that the condensation will be drained away without any possibility of the same extinguishing the burner.

My preferred construction of water-coil consists of a plurality of sections A, which are substantially shaped like an inverted V, in vertical cross section, and of course any

desired number of the said sections may be used, depending upon the required capacity of the water-heater. I prefer to make my water coil out of a length of piping, and in 5 making it the piping is wound around a conical-shaped body, and then when removed therefrom, it is placed over the lower supporting bars B, which are composed of a plurality of inverted V-shaped sections C, 10 which are in alinement. The upper supporting plates D are composed of a plurality of V-shaped sections E, the sections in each plate being in alinement. These plates D are then placed upon the coil of piping 15 and are pressed down upon the same, the sections E of each plate D, being positioned in the spaces F separating the sections C for the greater portion of their height. The outer edges G of each section C are provided with a plurality of notches H so positioned and shaped that the convolutions of the said sections A are forced by the said plates D into their respective notches. Each supporting bar B is provided at each 20 end with an extension I, and each supporting plate D is provided at each end with an extension J. Each extension J rests upon its associated extension I. Bolts K pass through the extensions I and J, and these 25 bolts are snugly held in place by the nuts L, thus firmly clamping the plates D and L, thus firmly clamping the plates D and the bars B together at their outer ends.

In Fig. 3 I show a plan view of the major portion of the upper supporting plates D. 30 These plates are preferably four in number, and a like number of the said bars B are used. Of course any desired number of the said plates and bars may be used. Through the section 2 of the water coil 3 is a central opening 4, according to my preferred form 35 of construction, and extending down into said opening and resting against the inner convolutions of the said section 2 are extensions 5 of the said plates D, and these extensions are connected together by a yoke piece 6, which rests upon the yoke piece 7 connecting together the side plates 8 of certain of the sections C of the bars B. 9 are bolts 40 passing through the yoke pieces 6 and 7 to 45 secure the plates D and bars B centrally together, and 10 are nuts screwed on the ends of the said bolts. The said plates D and bars B may be of course secured together at their points of contact by any suitable construction.

The convolutions of each of the sections A are spaced apart so as to provide for the circulation of the heated air therebetween. The convolutions of each of the said sections 50 extend partly underneath the convolution immediately thereabove, and this position of the said convolutions, together with their close proximity, prevents the formation of the condensation in the form of drops on 55 any of the convolutions except the lower-

most ones. When the condensation, for instance, collects on the under side of the convolution 11, by reason of the closeness thereto of the convolutions 12 and 13, before the said condensation can be formed into a drop, it will touch the said convolutions 12 and 13 and by capillary attraction will pass thereto and then thereover, on their inner sides, and will come in contact with the convolutions immediately therebelow. This 75 progress of the said condensation will be continued until it collects on the lowermost convolutions 14 from whence it drops.

From the foregoing it will be clear to one skilled in this art that the convolutions of the sections A are close enough together so as to enable me to determine positively the positions where the condensation will drop from. I of course may use any suitable type of gas burner, and I shall now describe the 80 construction of the gas burner I prefer to use. This burner comprises a mixer 15 which opens into a distributer 16. The lower portion 17 of the said distributer is preferably integrally formed with the mixer 85 15, and it is provided with horizontal side flanges 18. The side flanges 18 are connected together by the downward-curved flanges 19. The upper portion 20 of said distributer is also provided with horizontal side flanges 21, 90 and these side flanges are connected together by the upward-curved flanges 22. The said upper portion 20 is placed upon the said lower portion, and these parts are clamped together by nuts and bolts designated by the 100 common numeral of reference 23. The said flanges 19 and 22 are clamped over the ends 24 of the burner-rings 25 which are spaced apart. The mixed air and gas of course pass from the distributer 16 into the said burner-rings 25, and escapes therefrom through the holes 26. Upon referring particularly to Fig. 1, it will be noticed that the burner-rings 25 are positioned substantially beneath the apex of each section A, and therefore the position of the lowermost convolutions 14 will be, except for the outside convolutions, directly above the spaces separating the said burner-rings. Therefore, when the condensation drops from the said convolutions 14, it will not come in contact with the burner-rings 25, and consequently no portion of the burner will be extinguished. The under sides of the supporting bars B are so shaped that the condensation accumulating thereon will be caused to concentrate at certain points, and these said points will be so positioned that the condensation dropping therefrom will not come in contact with the burner. My preferred construction for 110 this purpose consists in providing the said supporting bars B with a plurality of pointed extremities 27, which are positioned 115 so that any condensation dropping therefrom will escape the burner-rings.

28 are a plurality of supports carried by the mixer 15 and designed to give support to the portions of the burner-rings 25 farthest removed from their supported ends 24.

5 In order to utilize the heated air as it escapes through the water coil 3, I preferably mount upon the top of the supporting plates D, a horizontal water coil 29.

30 are cross bars which are clamped down 10 upon the water coil 29 to keep it in place.

31 are bolts passing through the ends of the bars 30, and these bolts pass through the extensions 32 carried by the upper portions of the plates D. 33 are nuts screwing 15 on the said bolts.

The water, according to the construction of the water coil shown, enters into the coil 29 through the extension 34, and passes from this water coil into the extension 35 of 20 the water coil 3, and the hot water or steam escapes from this water coil through the discharge pipe 36. The apexes 37 of the supporting bars B support the top-most convolutions of the water coil 3. Of course it will 25 be understood that my particular make of water coil may be cast or otherwise made into the desired form. Although the burner-rings 25 are shown elliptical in cross section, they of course may be made circular or of 30 any other desired shape.

38 is the basin of my casing, and the same is preferably provided with an annular channel 39. I preferably support the water coil by means of screws 40 which screw 35 through the extensions I, and the heads of these screws rest upon the floor 41 of the said annular channel. By means of these screws I can adjust the position of the said water coil within the casing in order to keep 40 it horizontal, and to adjust its distance from the flame of the burner.

42 is a discharge opening formed in the basin 38 through which the condensation passes.

45 The cover or top 43 is carried by the basin 38, and this top is provided with an opening 44 through which the heated air escapes. I construct the said cover so that it will extend well above the water coil so as to provide 50 plenty of room for the circulation of air within the said casing in order to insure proper combustion.

It will be noticed upon referring to Fig. 1 that the condensation occurring on the convolutions of the water coil 29 will drop down 55 upon the convolutions comprising the sections A, and therefore this condensation will be carried away by the said sections after the manner already described. Of course the 60 water coil 29 does not form a part of my water coil 3, although I prefer to use it for the reason already set forth.

While I have described what I consider to 65 be the best embodiment of my invention, I desire it to be understood that the principles

can be embodied in different forms and I desire not to be limited beyond the requirements of the prior art, and the terms of my claims.

The lowermost convolutions 14 form 70 boundaries for what I may term the base of each section A, and it will be understood that the burner-rings 25 are positioned within said bases, and that the pointed extremities 27 of the supporting bars B are positioned above the spaces separating the said burner-rings 25, except for the outermost positioned of the set of said extremities, for the purpose already set forth. The middle extremities α are positioned above the opening 80 or spaces bounded by the central burner-ring. Although the extremities 27 and α are illustrated directly above the major portion of the distributor and mixer, it will be understood that the said distributor and 85 mixer may be positioned so that the condensation dropping from the said extremities will not collect thereon. The parts just described have been illustrated in the positions disclosed by Fig. 1 for the purpose of 90 ease of illustration. A certain amount of the condensation will drop from the convolutions 14 upon the said distributor and mixer, because these parts pass underneath the said convolutions. But the accumulation 95 of condensation on the said parts of the burner will be very small.

The sides of the section A, illustrated in Fig. 1, occupy an angle of 30 degrees to the vertical, and this is the angular inclination 100 of the sides of the sections in the water coils I have constructed. While this angle is a convenient one, still I do not confine myself to constructing the sides of the said sections at any particular angle provided the principle of my invention is not sacrificed.

What I claim as my invention is:

1. A new article of manufacture consisting of a water coil composed of piping formed into a plurality of sections spaced 110 apart and each section composed of a plurality of convolutions, the contiguous convolutions being spaced apart and laterally-disposed from the vertical whereby any given convolution extends a sufficient distance beneath the convolution immediately thereabove and whereby the condensation may 115 pass by capillary attraction from one convolution to another and collect on the lowermost convolution.

2. As a new article of manufacture, a water coil composed of a length of piping formed into a plurality of sections spaced apart and each composed of a plurality of convolutions, the contiguous ones being 125 spaced a short distance apart and laterally displaced from the vertical sufficiently so that any given convolution extends a sufficient distance underneath the one immediately thereabove in order that the condensa- 130

tion may drain from one convolution to another, and means for clamping said convolutions in relationship and constructed with portions extending therebelow and shaped to cause any condensation on said means to collect thereon in given positions.

3. As a new article of manufacture, a water coil composed of a length of piping formed into a plurality of sections spaced apart and each composed of a plurality of convolutions, the contiguous ones being spaced a short distance apart and laterally displaced from the vertical sufficiently so that any given convolution extends a sufficient distance underneath the one immediately thereabove in order that the condensation may drain from one convolution to another, and suitable means for clamping said convolutions and holding them in relationship.

4. As a new article of manufacture, a water coil composed of a length of piping formed into a plurality of two-sided sections spaced apart, and each composed of a plurality of convolutions, the contiguous ones being spaced a short distance apart and progressively increasing in diameter from the top to the bottom of the coil in one side of the sections, and decreasing in diameter from the top to the bottom of the coil in the other side of the said sections, so that any given convolution extends sufficiently underneath the one immediately thereabove in order that the condensation may drain from one convolution to another, and collect on the lowermost convolution, and suitable means for clamping said convolutions, and holding them in relationship.

5. As a new article of manufacture, a water coil composed of a plurality of two-sided sections spaced apart, the central section being provided with a central opening therethrough, and each composed of a plurality of convolutions, the contiguous ones being spaced a short distance apart, and progressively increasing in diameter from the top to the bottom of the coil, in one side of the sections, and decreasing in diameter from the top to the bottom of the coil in the other side of the said sections, so that any given convolution extends sufficiently underneath the one immediately thereabove in order that the condensation may drain from one convolution to another and collect on the lowermost convolution, and means for clamping said convolutions in relationship and constructed with portions extending therebelow and shaped to cause any condensation on said means to collect thereon, as set forth.

6. As a new article of manufacture, a water coil composed of a plurality of convolutions spaced the desired distance apart and forming a plurality of sections spaced apart, each of which is shaped substantially

like an inverted V, in vertical cross section, and laterally displaced from the vertical sufficiently so that any given convolution extends a sufficient distance underneath the one immediately thereabove in order that the condensation may drain from one convolution to another and collect on the lowermost convolution, as set forth.

7. As a new article of manufacture, a water coil composed of a plurality of convolutions spaced the desired distance apart and forming a plurality of sections spaced apart, each of which is shaped substantially like an inverted V, in vertical cross section and laterally displaced from the vertical sufficiently so that any given convolution extends a sufficient distance underneath the one immediately thereabove in order that the condensation may drain from one convolution to another, and collect on the lowermost convolutions, and suitable means for supporting the said convolutions and retaining them in position.

8. As a new article of manufacture, a water coil composed of a plurality of sections spaced apart, each shaped substantially like an inverted V, in vertical cross section, and composed of a length of piping formed into a plurality of convolutions, spaced a short distance apart, and laterally displaced from the vertical sufficiently so that any given convolution extends a sufficient distance underneath the one immediately thereabove in order that the condensation may drain from one convolution to another in each section, and collect on the lowermost convolutions, and suitable means for supporting the said convolutions and retaining them in position.

9. As a new article of manufacture, a water coil composed of a plurality of sections spaced apart, each shaped substantially like an inverted V, in vertical cross section, and composed of a length of piping formed into a plurality of convolutions, spaced a short distance apart, and laterally displaced from the vertical sufficiently so that any given convolution extends a sufficient distance underneath the one immediately thereabove in order that the condensation may drain from one convolution to another in each section, and collect on the lowermost convolution; a plurality of bars composed of sections, shaped substantially like an inverted V, in side elevation, extending into each of the said water coil sections, to support said convolutions, and each bar section being constructed with a pointed extremity positioned underneath the lowermost of the said convolutions; a plurality of plates each composed of a plurality of sections V-shaped in side elevation, said plate sections designed to fit down over the said convolutions composing the said water coil sections, and between the said water coil sections, and means

for clamping the said plates and bars together.

10. As a new article of manufacture, a water coil composed of a plurality of sections spaced apart, and each shaped substantially like an inverted V, in vertical cross section, the central section being provided with a central opening therethrough, and composed of a length of piping formed into a plurality of convolutions, spaced a short distance apart, and laterally displaced from the vertical sufficiently so that any given convolution extends a sufficient distance underneath the one immediately thereabove in order that the condensation may drain from one convolution to another in each section, and collect on the lowermost convolutions; a plurality of bars, centrally connected together by yoke pieces positioned underneath the central opening passing through said central water-coil section, and composed of sections shaped substantially like an inverted V, in side elevation, extending into each of the said water coil sections to support the said convolutions; the outer sides of the said bar-sections being provided with a plurality of notches to support said convolutions; a pointed extremity forming a part of each of the said bars and positioned below the lowermost convolutions of each of the said water-coil sections; a plurality of plates, centrally connected together by yoke pieces positioned with the central opening passing through said central water-coil section, each composed of a plurality of sections V-shaped in side elevation, said plate sections designed to fit against the said convolutions composing the said water-coil sections; means for clamping the said yoke pieces together, and means for clamping the outer ends of the said plates and bars together.

11. As a new article of manufacture, a water heater comprising a water coil composed of a length of piping formed into a plurality of convolutions spaced a short distance apart, and formed into a plurality of sections shaped substantially like an inverted V, in vertical cross section, and laterally

displaced from the vertical sufficiently so that any given convolution extends a sufficient distance underneath the one immediately thereabove in order that the condensation may drain from one convolution to another, and collect on the lowermost convolutions; suitable means for supporting said convolutions and retaining them in position, and provided with pointed extremities positioned underneath the said lowermost convolutions, and a gas burner positioned so that the flame therefrom will be within the base of each of the said sections.

12. As a new article of manufacture, a water heater comprising a water coil composed of a length of piping formed into a plurality of convolutions spaced a short distance apart, and formed into a plurality of sections shaped substantially like an inverted V, in vertical cross section, and laterally displaced from the vertical sufficiently so that any given convolution extends a sufficient distance underneath the one immediately thereabove in order that the condensation may drain from one convolution to another and collect on the lowermost convolutions; suitable means for supporting said convolutions and retaining them in position, and provided with pointed extremities positioned underneath the said lowermost convolutions; a gas burner positioned so that the flame therefrom will be within the base of each of the said sections; a casing composed of a basin having an annular channel near the top thereof, and provided with a drainage opening; adjustable means carried by the supporting means for said convolutions and resting against the floor of said annular channel, and a cover for said basin of the desired size provided with a ventilating opening.

In testimony whereof I have affixed my signature in presence of two witnesses.

REGINALD FOWLER REED.
